UNITED STATES PATENT OFFICE.

ARTHUR G. ROGERS, OF MERIDEN, CONNECTICUT, ASSIGNOR TO C. ROGERS & BROS., OF SAME PLACE.

DESIGN FOR A SPOON.

SPECIFICATION forming part of Design No. 22,560, dated June 27, 1893.

Application filed May 29, 1893. Serial No. 475,970. Term of patent 14 years.

To all whom it may concern:

Be it known that I, ARTHUR G. ROGERS, of Meriden, in the county of New Haven and State of Connecticut, have invented a new 5 Design for the Handles of Spoons, Forks, &c.; and I do hereby declare the following, when taken in connection with the accompanying drawing and the letters of reference marked thereon, to be a full, clear, and exact description of the same, and which said drawing constitutes part of this specification, and represents a face view.

This invention relates to a design for the handles of spoons, forks, and like articles of 15 table-service, and consists in the configuration and ornamentation as shown in the accompanying illustration.

The handle expands in width from the bowl, by a series of gradually lengthening scallops, 20 A, to the tip B, where it terminates in a rounded shape. Upon the surface of the face of the handle a vine-like ornamentation of leaves

and scrolls C, extends up each side, from about midway the length of the handle, its lower ends meeting a small circular boss D, 25 which is surmounted by a leaf-like form E, and having below it a conventionalized leaf-form F. The vine-like ornamentation conforms to the shape of the expanding handle, and its meeting edges at the center-top are 30 connected by a small boss G, having a segmental scalloped ornamentation H, above and below it.

I claim—

The design for the handles of spoons, forks, 35 and like articles, as described and shown in the accompanying illustration.

In testimony whereof I have signed this specification in the presence of two subscribing witnesses.

ARTHUR G. ROGERS.
